(57) **CLAIM**

The ornamental design for a lollipop, as shown and described.

DESCRIPTION

FIG. 1 is a front, left side perspective view of a first embodiment of a lollipop showing my new design;

FIG. 2 is a right side elevation view thereof;

FIG. 3 is a back elevation view thereof;

FIG. 4 is a front, left side perspective view of a second embodiment of a lollipop;

FIG. 5 is a rear, left side perspective view thereof; and,

FIG. 6 is a left side elevation view thereof.

The broken lines shown in FIGS. 1-6 illustrate portions of the lollipop, that form no part of the claimed design.
